United States Patent Office.

EDWIN YANCY, OF UTICA, NEW YORK.

Letters Patent No. 68,405, dated September 3, 1867.

IMPROVEMENT IN HORSE HAY-FORKS.

The Schedule referred to in these Letters Patent and making part of the same.

TO ALL WHOM IT MAY CONCERN:

Be it known that I, EDWIN YANCY, of Utica, in the county of Oneida, and State of New York, have invented certain new and useful Improvements in Hay-Forks; and I do hereby declare that the following is a full and complete description of the same, reference being had to the accompanying drawings, making a part of this specification, in which—

Figure 1 is a side view of the fork with the point thrown down.

Figure 2 is a front view with the point thrown out.

Figure 3 is a side view of the same.

Like letters of reference refer to like parts in the views.

In the drawings, A is the shank of the fork, to the lower end of which is pivoted, at the point X, the foot B, the upper end terminating in a loop, C. Immediately below this loop projects an arm, D, fig. 2, to which is pivoted the curved lever E. To the heel of the foot or point B is pivoted a link, F, which link is attached to the shank by a loop, G, through which it slides, and by which it is kept in its proper position. The upper end of this link is connected to the curved lever E by means of a hook, H, which is secured in the end of the link, and by means of which the point is operated in the following manner: When the fork is in the position shown in fig. 1, with the point thrown down, it is forced into the hay, over which it is to be suspended by the loop C, the end of the curved lever E forming a handle to aid in forcing it into the hay. When thus inserted in the hay the point is thrown out in the position shown in fig. 3, by moving the lever E up from the position indicated by the dotted lines α to α' , thus causing the curved side of said lever to press on the top of the link F which forces it down, thus depressing the heel and raising the point of the foot B, as indicated in fig. 3, the lever E being turned till the square end, forming a rest, I, comes upon the top of the link F, and when in this position the point cannot be thrown down by any weight of hay that may be lifted on said point, as the end of the link will press firmly against the square end of the lever, as represented in fig. 2. When the fork is loaded it is then drawn up out of the hay and moved to the mow or place where it is to be deposited, and when the square end I of the lever is removed from the end of the link, the weight of the hay will throw the point down into the position seen in fig. 1, and thus raise the link F, throwing the lever back into its former position, and dropping the hay, as desired, when the fork can be carried back and reloaded in the same manner as before.

What I claim as my improvement, and desire to secure by Letters Patent, is—

The curved lever E provided with the rest I, and pivoted to the arm D, in combination with the hook H, link F, point B, and shank A, arranged as and for the purpose substantially as set forth.

EDWIN ^{his} YANCY.
